UNITED STATES PATENT OFFICE.

WILLIAM T. BOICE, OF MOLINE, ILLINOIS.

HORSESHOE CARD GAME.

Application filed August 6, 1924. Serial No. 730,422.

My invention relates to a pack of cards, whereby a horse-shoe card game can be played.

It is an object of this invention to provide a card game which can be played as nearly like an outdoor game of horse-shoes as is possible.

It is a further object to provide a pack of cards illustrated to represent the various positions a pitched horse-shoe, or horse-shoes, may take about a pitching stake after being pitched, said cards having relative values indicating the distances the shoe or shoes may lie from the stake; and, also, indicating hubbers, ringers and the arrangement of horse-shoes after a hubber or ringer has been knocked from a stake.

It is a further object to provide a game which can be played by from two to four teen people, which has simple rules and will provide an interesting and delightful amusement.

These and other objects and advantages of the invention will be fully set forth in the following description made in connection with the accompanying drawings, in which like reference characters refer to the same parts throughout the different views, and in which—

Fig. 1 is a perspective view of a pack of cards having a so-called zero-ringer card lying on the top thereof;

Fig. 2 is a face view of one of the ordinary cards;

Fig. 3 is a face view of another of the ordinary cards;

Fig. 4 is a face view of a hubber card;

Fig. 5 is a face view of a good luck ringer card;

Fig. 6 is a perspective face view of a Dat A Boy card; and

Fig. 7 is a face view of a double ringer card.

Upon the cards the illustration of a horse-shoe pitching stake A is printed, said stake being placed adjacent one end of the ordinary hubber and zero-ringer cards and adjacent the central portion of the good luck ringer, double ringer and Dat A Boy cards.

The illustrations of one or two horse-shoes B are printed upon the cards, said horse-shoes being placed at varying positions about stake A corresponding to the actual positions a horse-shoe or horse-shoes may take after being pitched in an actual outdoor game. Various numerals C on each card are

illustrated at each corner of all the various types of cards except the Dat A Boy cards and double ringer cards and may be placed thereon if so desired. The cards may be illustrated with an attractive design on their backs or may be left plain, as desired.

In the ordinary cards, Figs. 2 and 3, but one horse-shoe B is shown, said shoe being situated at a distance from the post A, the number of length units therefrom indicated by the numeral C, which vary with each card in a single suit. The hubber cards, Fig. 4, represent what is called a "hubber" or "leaner" in a game of horse-shoes, said hubber or leaner being the position taken by a horse-shoe B leaning against a stake A. The numerals C on the hubber cards do not represent the distance the horse-shoe is situated from the stake but are preferably represented as being the numeral "2" as shown.

The so-called zero-ringer cards, Fig. 1, represent what is called a "ringer" in the game of horse-shoes, said ringer being the position a horse-shoe takes when encircling a stake. Any appropriate numerals C may be printed on the zero-ringer cards but preferably the numeral "1" is used.

The so-called good luck ringer cards consist of cards having "good luck" prominently printed thereon, a ringer horse-shoe about the stake, and another horse-shoe adjacent thereto. Various numerals may be illustrated on these cards.

The Dat A Boy cards, Fig. 6, have "Dat A Boy" printed prominently on their faces and show two horse-shoes situated about a pitching stake, said cards representing the position taken by two horse-shoes around a stake after one of the shces has knocked a hubber or ringer shoe off the stake. "Dat A Boy" is an expression often used by an on-looker watching a game of horse-shoes after a brilliant play has been made. The double ringer cards Fig. 7 represent the position of two ringers on a stake.

The deck of cards consists preferably of two suits—a red and a blue suit, Figs. 1, 3 and 5 being illustrated as of the blue suit, and Figs. 2, 4 and 6 as being of the red suit. A number of different suits having different designating colors, however, can be used. In each suit there are eighteen ordinary cards, numbering from 3 to 20 inclusive, three hubber cards, numbered 2, one zero-ringer card, being numbered 1, four good-

luck ringer cards numbered from 1 to 4, inclusive, two double ringer cards, and two Dat A Boy cards being numbered 1 or having no number thereon. There are then 5 twenty-nine cards in each suit or fifty-eight cards in all. The number of cards of each type can be varied as desired. The game can be played with any of the different types of cards left out of the deck if desired.

10

Rules.

The cards are first shuffled and preferably four cards dealt to each player. Although a greater number of cards can be dealt if desired. The person to the right of the dealer leads, playing one of his cards. The players to the right of the person leading then play in turn until all have played. 15 whereupon the one playing the high card 20 will take the trick. The winner of the trick then leads and the cards are played as before, every succeeding trick winner leading until all the cards dealt have been played. The game may consist of either 11 or 21 25 points. If this number of points is not obtained by any one person or group of persons playing together after the cards have been dealt out once, all the cards are reshuffled and the game proceeds as before 30 until the required number of points are obtained. The players can be divided into partners or each one may play in his individual capacity.

The highest card played on a trick will 35 take the trick. Every trick counts one point except those taken by a hubber or ringer card, those counting 2 and 4 points, respectively. If the double ringer cards are used 40 a trick taken by a double ringer card will count eight points. When two cards of the same kind are played, that is, cards of the same type and being designated by the same numeral, the last card played is high and takes the trick unless topped by another 45 card. The highest of the ordinary cards are the "3" cards, while the lowest ordinary cards are the "20" cards. The intermediate cards vary in trick taking value as their number decreases. The six hubber cards are 50 higher than any of the ordinary cards and will take any of them. The zero-ringer cards are of next higher value after the hubber cards. The four Dat A Boy cards will take any trick and are the highest cards 55 in the deck. The double ringer cards are next to the highest cards in the deck and will take everything but the Dat A Boy cards.

The eight good-luck ringer cards are used 60 as follows: After the deal, all those having

good-luck ringer cards turn them face upward on the playing table and a corresponding number of new cards are dealt the holders thereof off the pack. A good-luck ringer card may be played at any time during the 65 course of the game by the party holding the same in conjunction with any other card, reducing the number indicated on the other card played by the number of points indicated on the good-luck ringer card and 70 thereby increasing the trick-taking value of the other card. A low ordinary card can then be increased in value to take a higher ordinary card, or an ordinary card can be increased in value to take a hubber or zero-ringer card. Certain cards in the deck can 75 then be increased in value to take anything played except a double ringer or Dat A Boy card. If a trick is taken by a good-luck ringer card in conjunction with another 80 card, it will, of course, count four points for the winner of the trick.

The rules of the game can be considerably varied if desired.

From the above description it is seen that 85 I have provided a simple and attractive card game which accomplishes the objects herein set out.

It will, of course, be understood that various changes may be made in the form, 90 number, details and proportions of the cards without departing from the scope of my invention, which, generally stated, consists in the matter shown and described and set forth in the appended claims.

What I claim is:—

1. A pack of cards for playing the game of horse-shoes, comprising one or more series of cards, certain of said cards representing the various distances a pitched horse-shoe may lie from a pitching stake, and others representing good-luck cards.

2. A pack of cards for playing the game of horse-shoes, certain of said cards representing the various distances a pitched horse-shoe may lie from a stake, others representing hubbers, others representing ringers, others representing lucky cards, others representing double ringer cards, and others representing the position of two horse-shoes around a pitching stake after a ringer or hubber has been knocked off of the stake.

3. A pack of cards for playing the game of horse-shoes comprising consecutively numbered cards, hubber cards, zero-ringer cards, good-luck ringer cards, double ringer cards and Dat A Boy cards.

In testimony whereof I affix my signature.

WILLIAM T. BOICE.
